DRAFTING INSTRUMENT

John Arlon Buick, Norfolk, Va.

Application August 15, 1951, Serial No. 241,975

1 Claim. (Cl. 33—93)

1

The present invention relates to drafting instruments, and more particularly to an instrument for use on drawing boards and the like for drawing and marking lines at various predetermined angles with respect to a reference edge.

One object is to provide a drafting instrument having a pivoted straight edge provided with an indicator arm which is movable over a protractor scale to indicate the angular position of the pivoted straight edge.

Another object is to provide a drafting instrument, including a tri-square to which is pivoted a straight edge such that the opposite sides of the tri-square may be used as a reference edge when the device is employed on a drafting board for marking or drawing lines on a drawing.

Another object is to provide a drafting instrument, including a pivoted straight edge having an indicator arm adjacent the pivot point of said straight edge, which is arranged to cooperate with a protractor scale so that both sides of the straight edge will be unobstructed to permit the drawing of lines on both sides thereof.

Another object is to provide a drafting instrument having a combination straight edge which is pivotally attached to one corner of a tri-square, and is provided with locking means for holding the straight edge arm in a predetermined angular position with respect to the opposite sides or reference edges of the tri-square.

Another object is to provide a drafting instrument having a locking element which can be quickly and easily manipulated to lock the combination straight edge arm in a pre-selected angular position.

Another object is to provide a guide strip for maintaining the indicator arm in position on the surface of the tri-square which can be conveniently employed for lifting the instrument with respect to the drawing surface by inserting the fingers thereunder so that in the event that ink or other drawing fluid is employed, smearing and the like will not occur.

Another object is to provide a locking member for maintaining the straight edge arm in a pre-selected angular position which includes cooperating threaded fasteners, which may be formed of a resinous plastic composition having an enlarged head portion at one end to overlie a relatively large area of the indicator arm adjacent the pivot point of said straight edge arm, and thereby securely lock the straight edge arm in a predetermined position.

Other objects and advantages of the invention will become apparent during the course of the

2

following description of the accompanying drawing wherein:

Figure 1 is a plan view of the drafting instrument showing the straight edge arm in its fully extended position in dotted lines, and its retracted position in full lines. The indicator arm is attached to the straight edge arm adjacent the pivot thereof, and is shown in cooperation with a protractor scale.

Figure 2 is an oblique cross-sectional view taken on line 2—2 of Figure 1, and looking in the direction of the arrows to illustrate the indicator arm and the combination retainer strip therefor and finger grip.

Figure 3 is an oblique cross-sectional view taken on line 3—3 of Figure 1, and looking in the direction of the arrows to illustrate the arm locking threaded fastener unit, and the manner in which the arm is frictionally locked in a pre-selected angular position.

Figure 4 is a fragmentary bottom or rear elevational view, showing the manner in which the straight edge arm is pivotally connected to the base or tri-square, and the manner in which one end thereof is beveled to limit movement of the straight edge arm beyond a 90° angular position with respect to one of the reference edges of the base or tri-square, and

Figure 5 is a fragmentary cross-sectional view of a modified form of straight edge arm locking means, including separable threaded fastener elements one of which may be formed of a synthetic resin plastic composition similar to the base and pivoted straight edge.

In the drawing, and more in detail there is shown a base member designated 5 which may be formed of transparent clear synthetic resin plastic or Celluloid, and said base is shaped in the form of a 45° angle tri-square having reference edges 6 and 7 extending at an angle of 90° with respect to one another, and connected at their outer ends by a hypotenuse edge 8. The right angle corner 9 connects the edges 6 and 7, while the opposite corners 10 and 11 form included 45° angles. The base or tri-square 5 is provided with an opening 12 having straight edges 13 and 14 parallel with the reference edges 7 and 8 respectively and a curved edge 15. The straight and curved edges 13—14 and 15 are connected by curved corner portions 16, 17 and 18 for use in drawing small curved lines on various radii.

The triangular base 5 or 45° angle tri-square may be placed on a drafting board with either 55 of the opposite reference edges 6 or 7 in registry

with a reference line in a conventional manner. Usually, a T-square is employed for this purpose.

Pivotedly attached to the corner 11 of the triangular base is an arm 20 which is pivotally connected by means of a pivot screw 21 to the base 5, and said pivot screw 21 extends through an opening in the corner 11 and similarly passes through an opening in the arm 20, so that the threaded end of said pivot screw may receive a correspondingly threaded knurled clamping nut 22. Attached to the underside of the arm 20 is a straight edge arm 23 (Figs. 1 and 4), and said straight edge arm 23 is diagonally cut at the upper and lower portions as at 24 and 25 to form a continuation of the reference edge 7 and abut the hypotenuse edge 8 respectively. It is intended to form the pivoted straight edge arm 23 and arm 20 of a synthetic resin plastic or Celluloid composition similar to the base 5, such that the draftsman may have clear vision of the drawing on which the instrument is used and other delineations thereon. In the event that the straight edge arm 23 is formed of a synthetic resin plastic composition, the arm 20 may be joined thereto by a plastic to plastic adhesive, or if desired, the arm 20 may be integrated with the straight edge arm 23 in the usual manner.

Formed integral with the arm 20 is an indicator arm 27 which extends at an angle approximately 45° to the pivoted straight edge arm 23, and said arm 27 is connected to the arm 20 by an arcuate portion 28 (Fig. 1) extending along a radius with the pivot screw 21 as its center. The arcuate edge 28 is adapted to be clampingly engaged by a locking member, including a locking screw 29 having an upper threaded end and a head 30 on the opposite end which is countersunk in an opening in the corner 11 spaced from the pivot screw 21 a distance slightly greater than the radius of the arcuate edge 28. A locking knurled thumb nut 31 is provided with an internally threaded opening for receiving the correspondingly threaded end 29 of the screw 30, and said knurled thumb nut 31 is provided with a flanged lower portion 32 adapted to overlie the arcuate edge 28 so as to frictionally engage the arm 20 adjacent the edge 28 and hold the straight edge arm 23 in a preselected angular position.

The indicator arm 27 is adapted to cooperate with a protractor scale 34, and the end of said arm is provided with a datum line 35 marked or otherwise applied to the beveled end edge 36 thereof so that it will register with the various degree markings 34 of the protractor scale. The protractor scale is marked with legends or numerals 37 which read from zero to 45 degrees, and with numerals 38 reading in a reverse direction from 45 to 90 degrees. Thus, both reference edges 6 and 7 may be used by simply turning the instrument about an angle of 45°.

Mounted on the triangular base 5 is a retainer strip 40 which has its ends angularly bent as at 41 to provide offset foot portions 42. The offset foot portions 42 are riveted or otherwise secured as at 43 to the triangular base 5, and is arranged above the free end of the indicator arm 27 so as to maintain said arm in position with the beveled end 36 projecting or presented to the protractor scale 34. When drawing angular lines, the draftsman may insert his fingers beneath the retaining strap 40 to facilitate lifting the instrument from the drawing board when it is desired to change the position thereof.

In the modified form of the invention shown

in Figure 5, a separable threaded fastener element is shown which can be substituted for the locking and pivot screws illustrated in the form of the invention shown in Figures 1 to 4 inclusive.

5 In the event that the pivot screw 21 and retaining nut 22 is replaced, the separable threaded fastener shown in Figure 5 may be used both as a pivot screw and locking means. In Fig. 5 the base 5a is the same as before, and includes a triangular base similar to that shown in Fig. 1. The arm 20a is adapted to be pivotally connected to the base 5a by means of a tubular fastener element 50a having a head 51a which is received in the enlarged portion of an opening 52a in the base 5a. The fastener element 50a is provided with an internally threaded bore 53a and said fastener is adapted to extend through an opening 54a in the arm 20a such that it projects therebeyond a slight distance. The tubular threaded fastener 50a may be formed of a synthetic resin plastic composition similar to the base 5a. The tubular threaded fastener 50a is adapted to receive the externally threaded portion 55a of a retaining screw having an enlarged head portion 56a and a downwardly directed rim portion 57a spaced from the externally threaded portion 55a by an annular channel 58a. Thus, the arm 20a may be frictionally and clampingly secured to the base 5a by turning the knurled peripheral portion (not shown) of the rim section 57a in a direction to thread the externally threaded portion 55a in the internally threaded portion 53a of the cooperating tubular fastener 50a.

35 If the locking fastener shown in Figure 5 is employed in lieu of the locking screw and nut 29-31 shown in Figs. 1 to 4 inclusive, the downwardly directed rim portion 57a will engage the arm 20a and overlie the arcuate edge thereof to lock the arm in a pre-selected position when the head 56a is turned in a right direction. The cooperating fastener element 50a shown in Fig. 5, may likewise be formed of a synthetic resin plastic of a color in contrast to the base and pivoted straight edge arm as well as the indicator arm.

45 It will thus be seen, that the straight edge arm 23 in Figs. 1 to 4 has its opposed edges in parallel relation one with the other, and with the hypotenuse edge 8 when the instrument is 50 in its retracted position. When in this position, 45 degree lines may be drawn in substantially the same manner as a tri-square is employed by placing the reference edges 6 and 7 against a reference line or surface on the drawing board.

55 When it is desired to draw lines from zero to 45 degrees, the reference edge 7 is placed against a horizontal or longitudinal reference surface. Similarly, by placing the reference edge 6 against a horizontal reference surface, angles 60 from 45 to 90 degrees may be drawn. Obviously, the triangular base 5 or tri-square can be placed in other positions so that the straight edge arm 23 can be adjusted to various predetermined angular positions and held therein by the locking fastener elements 29-31 shown in Figs. 1 to 4 inclusive, and 50a-55a shown in Fig. 5.

65 It is to be understood, that the forms of the invention herewith shown and described are to be taken as preferred embodiments thereof, and that various changes in the shape, size and arrangement of parts may be resorted to without departing from the spirit of the invention or the scope of the subjoined claim.

What I claim is:

In a drafting instrument, a triangular base

having a hypotenuse the obstruction of which is held to a minimum at all times of use, a straight edge arm having one end pivotally connected to a corner of said triangular base at a point in the angle between the hypotenuse and base and near the intersection thereof, an indicator arm integrally connected to said straight edge arm adjacent the pivoted end thereof and projecting over the base to cooperate with a protractor scale thereon, a guide strap having its ends affixed to said triangular base adjacent the ends of said scale to guide said indicator arm in close proximity to the graduations of said scale, an arcuate portion connecting said straight edge arm and said indicator arm, the rim of the arc extending along a radius having the common pivot of the straight edge arm and the indicator arm as its center, said arcuate rim lying in close proximity to said center, and a threaded fastener for holding said straight edge and indicator arms 20

in a position of angular adjustment, said threaded fastener being arranged on the base between said arms with a rim of the fastener overlying and frictionally engaging said arcuate rim.

JOHN ARRON BUICK.
